UNITED STATES PATENT OFFICE.

PAUL A. N. WINAND, OF PHILADELPHIA, PENNSYLVANIA, ASSIGNOR TO
THE OTTO GAS ENGINE WORKS, OF SAME PLACE.

GAS-GENERATOR.

SPECIFICATION forming part of Letters Patent No. 622,744, dated April 11, 1899.

Application filed January 13, 1896. Renewed January 12, 1899. Serial No. 702,001. (No model.)

To all whom it may concern:

Be it known that I, PAUL A. N. WINAND, a subject of the King of Belgium, and a resident of Philadelphia, in the county of Philadelphia and State of Pennsylvania, have invented certain new and useful Improvements in Gas-Generators, of which the following is a specification.

In my improved organization I provide an annular reservoir for the fuel located at the top of a generator and feed the fuel from the reservoir to the generator circumferentially around a centrally-arranged water-cooled bell, dome, or chamber, through which the products of combustion or gas is taken off. The effect of so feeding a gas-generator, which, however, is not new, is that the supplied fuel forms a bed which slopes naturally from the periphery of the column of fuel downwardly toward the center. This manner of feeding and the consequent arrangement of the fuel within the generator induces the blast introduced at the bottom to pass up centrally through the column of fuel to a greater extent than it will pass along or in proximity to the interior walls of the generator. The production of clinkers and the formation of channels or passages in the body of the fuel have a tendency to occur at or adjacent to the walls of the generator, and in my organization since the blast passes through the column of fuel centrally these objectionable features are to a very considerable extent avoided.

The generator fuel-reservoir may be closed by the ordinary cap or top plate of the generator, in which feed-openings at suitable intervals and provided with proper covers may be formed.

Another feature of my invention is a special organization involving the attachment and mounting of the outlet-pipe for gas or products of combustion from the generator centrally, but in such manner as to permit of its ready detachment and removal to afford access to the central sloping body of fuel beneath the bell or dome.

My invention also includes certain improvements in the grate involving a central stationary blast-inlet and a grate having circu-

larly-rocking movement for stirring or agitating the whole bed of fuel and forcing out the ashes at the base thereof.

In the accompanying drawings, Figure 1 is a vertical section through a generator constructed in accordance with my improvements; Fig. 2, a plan view thereof; Fig. 3, a horizontal section on the line 3 3 of Fig. 1, and Fig. 4 a detail view showing another form of water-cooled bell or vessel in the top of the generator.

The shell and interior walls of the generator may be of any usual and appropriate construction except that the upper faces or edges of the walls are preferably inclined from the periphery inwardly and downwardly, as indicated at A. Centrally within the casing of the generator I provide a bell or inverted vessel B, which may be suitably secured to the top plate C and is formed with double walls d d, providing an annular chamber for the circulation of water, which may enter at d' and leave at d².

Fig. 4 indicates another style of water-cooled bell or dome B. In this case the bell is formed with a spiral rib or with annular ribs b running around its exterior. Water is supplied from an adjustable tap b' to a trapped pipe b², whose lower end passes through the top plate of the generator and terminates in proximity to the exterior of the bell at the top thereof. The supply of water will not be such as to impair the proper action of the generator, and its flow will not be unduly impeded by the solid fuel lying against the exterior face of the generator.

The water-cooling of the bell enables me to dispense with the use of fire-brick or other refractory material in its construction and also tends to reduce the temperature within the bell, which in some cases makes it necessary to further cool the gas by the use of a water seal and scrubber. Between the exterior face of the bell B and the walls and top plate of the generator an annular fuel-reservoir E is thus formed, and the sloping tops A of the walls and the annular exterior of the bell B direct the fuel therein to the outlet F between the edge of the bell and the sloping face of the wall. The fuel is there-

fore fed circumferentially to the generator and will tend to arrange itself in the general manner or condition indicated in the drawings. The top plate is formed with fuel-feeding apertures C', provided with removable covers, and from time to time the reservoir may be filled. The usual blast introduced centrally at the base of the column of fuel will find a more ready path through the central portion of the fuel, and the volume passing through the fuel will gradually decrease from the center toward the walls of the generator. I have found by practical use that in a generator so constructed the objectionable production of clinkers at the walls of the generator, and the consequent obstruction to the proper and uniform descent of the column of fuel, does not occur. I have also found that the formation of objectionable channels or passages in the fuel, which usually occur adjacent to the walls of the generator and permit the passage of the blast through the fuel without proper contact with or distribution through it, is obviated. The top plate C is provided with a hub or short flanged pipe-section G, communicating with the interior of the dome or bell B, and to it the gas offtake or outlet pipe H may be detachably connected by swinging screw-fastenings h of usual construction. The pipe is then extended laterally and formed with a bend or downwardly-extending elbow H', the lower end of which is immersed in a water seal H'', mounted upon the upper end of the pipe H'. A frame or spider I, secured across or in the mouth of the pipe H', has mounted in it a spindle or shaft I', that passes through a bearing I'', formed in the pipe H, and is supported to its upper end in a block I'. The fastening devices h may be opened or released and the pipe H swung laterally, as indicated in Fig. 2, being supported by and turning upon the spindle I', thus affording access centrally to the bed of fuel in the generator.

At the base of the generator is the usual ash-pit, and in it is mounted the grate or plate supporting the base of the column of fuel, the construction being as follows: An annular flanged ring or frame k is suitably supported at the base of the generator-chamber, and within it is arranged a circularly-rocking plate K', supported loosely upon posts k, seated in sockets in the under side of the plate and carried in the ends of arms of a spider-frame L, which is supported loosely by a central post L', seated in a central socket in the under face of the spider. A horizontal shaft M has bearings in bushings N, located in the walls or shell of the furnace and provided with handles n. One or both ends of the shaft M may be provided with a crank-handle M', by which it may be rotated. Two circular cams or eccentrics m, oppositely fixed upon the shaft M, are embraced by the jaws of the bifurcated radial spider-arms L'. The revolution of the shaft

M will therefore impart to the plate K' a circularly-rocking motion that will stir or agitate the bed of fuel and force out the ashes at the base over the flange of the ring or frame K. An adjustable ring K'' may rest upon the flange of the frame K and serve to prevent the discharge of ashes when it is only desired to stir or agitate the bed of fuel. To permit free discharge of the ashes, the ring K'' may be elevated into the position shown by dotted lines. The blast-inlet pipe O passes through a central aperture in the plate K' and may be provided with the usual guard-cap O'. The aperture in the plate may be sufficiently larger than the exterior diameter of the blast-pipe to permit the circularly-rocking motion of the plate or grate K'. I prefer, however, to form a curved boss o on the blast-pipe, to the curve of which the edge of the plate would conform during the rocking movement.

I claim as my invention—

1. In a gas-generator the combination of the outlet-pipe H, the inverted vessel or bell within the generator-chamber and detachably connected with the pipe, a spindle or shaft upon which the outlet-pipe may be swung horizontally, the pipe H', with which the outlet-pipe communicates, and a water seal arranged in the joint between the outlet-pipe and the pipe H'.

2. The combination of a gas-outlet pipe, H, the pipe, H', carrying a water seal, H'', in which the outer end of the pipe H is immersed, the frame, I, the spindle, I', having a bearing in the wall of the pipe, H, whereby the pipe, H, may be swung horizontally, and means for detachably connecting the other end of the pipe with the gas-outlet of the generator.

3. The combination with the gas-generator, of an offtake-pipe detachably connected at one end with the gas-outlet of the generator, and pivoted at the other end to move about a vertical axis, and a water seal in which the end of the pipe works.

4. The combination of the generator-chamber, a stationary, centrally-arranged blast-inlet at the bottom of the generator-chamber, and a rocking plate or grate having an aperture through which the blast-inlet extends and about which the grate oscillates as a center.

5. The combination of a rocking plate or grate located at the base of the generator-chamber, the loosely-mounted spider upon which the plate is loosely supported, the shaft and its cams working between the jaws of the bifurcated arms of the spider, substantially as set forth.

6. In a gas-generator the combination of the rocking plate or grate located in the base of the generator-chamber, a stationary blast-inlet pipe passing centrally through said plate and about which the plate rocks as a center, and means for imparting to the plate a rocking movement.

7. The combination of the rocking plate or

grate, means for actuating it, its annular stationary frame, and a guard or ring, as K², to prevent the discharge of the ashes or fuel when the mass of fuel is agitated by the rocking of the plate.

5 S. The combination with the generator-chamber of the plate arranged at the bottom thereof, the blast-pipe extending centrally through the plate and having bearing-surfaces about which the plate rocks, the spider,

a support upon which it rocks, a series of uprights mounted on the arms of the spider, and a loose connection between the upper ends of the uprights and sockets in the plate.

In testimony whereof I have hereunto subscribed my name.

PAUL A. N. WINAND.
